BALL POINT PEN

Patrick J. Frawley, Jr., Los Angeles, Calif., assignor, by
mesne assignments, to Paper Mate Manufacturing Com-
pany, Culver City, Calif., a corporation of Delaware

Application April 19, 1954, Serial No. 30,065

Term of patent 14 years

(Cl. D74—17)

Figure 1 is a front elevation of a ball point pen, embodying my new design;

Fig. 2 is a side elevation of the ball point pen; and
Fig. 3 is a top plan view of the ball point pen.

The characteristic feature of my design resides in the combination on the pen disclosed of the contrasting area on the clip portion, the horizontal ridges extending downwardly therefrom and the annular band of similar contrast on the barrel portion thereof, all as shown.

I claim:

The ornamental design for a ball point pen, substan-
tially as shown and described.
